UNITED STATES PATENT OFFICE.

WILLIAM W. BALDWIN, OF CLEVELAND, OHIO.

DESIGN FOR A STOVE.

SPECIFICATION forming part of Design No. 25,066, dated January 21, 1896.

Application filed November 7, 1895. Serial No. 568,283. Term of patent 7 years.

To all whom it may concern:

Be it known that I, WILLIAM W. BALDWIN, a citizen of the United States, residing at Cleveland, in the county of Cuyahoga and State of Ohio, have invented and produced New and original Design for Stoves, of which the following is a specification, reference being had to the accompanying drawing, showing a perspective view of a stove in which my invention is found.

The essential feature of my design consists of a stove-top A, provided with ornamentation, as hereinafter described, the substantially rectangular body portion B, also suitably ornamented, and the ornamented base C.

The top A has a base which inclines outwardly to the border edge 3, and is provided with leaf figure-work 4 extending upward in uniform design. Above border 3 is open scrollwork 5 running to a second step in the top, which is raised visibly above the first part and has open scrollwork 6, and is surmounted by a globe-shaped vase 7 with ornamental decorations at its sides and top.

The body B has two ornamental horizontal borders 7' and 8 at and near its bottom, with open foliage-work 9 between said borders and over the surface above border 7' to the decorated base 4 above, while distinct figured columns 10 distinguish the corners of the

body B from top to bottom thereof and between the borders 7' and 8.

The base portion C of the stove has at its extreme bottom a border covered with scrolls 11 inclosing occasional rosettes or headed designs 12, and stars 13, with scrolls 14 running off into the border, serve as ornamentation to the legs of the stove. Along the top of the said border is a ribbed ledge 15, and above this ledge are the peculiarly-ornamented doors 16 having large beaded center ornamentations 17. At the sides are foot-rests with attractive outwardly-curved and decorated supports 18 starting from the base and running into the body portion of the stove at their top between the borders 7' and 8. 35 40 45

What I claim is—

1. In a stove, the design for the top, substantially as herein shown and described.
2. In a stove, the design for the body, substantially as herein shown and described. 50
3. In a stove, the design for a base, substantially as herein shown and described.
4. The design for a stove, substantially as herein shown and described.

WILLIAM W. BALDWIN.
